UNITED STATES PATENT OFFICE

MAX KLEIN, OF NEW YORK, N. Y., ASSIGNOR TO SHAPIRO AND ARONSON, INC.,
OF NEW YORK, N. Y., A CORPORATION OF NEW YORK

DESIGN FOR A LIGHTING FIXTURE

Application filed November 5, 1931. Serial No. 41,633. Term of patent 3½ years.

To all whom it may concern:

Be it known that I, MAX KLEIN, a citizen of the United States, residing at 74 Sterling St., New York city, in the county of Kings and State of New York, have invented a new, original, and ornamental Design for a Lighting Fixture, of which the following is a specification, reference being had to the accompanying drawing, forming a part thereof.

The single figure of the drawing is an elevational view showing the new design. The circumferential portions of the fixture not shown have substantially the same appearance as the circumferential portions set forth.

I claim:

The ornamental design for a lighting fixture, substantially as shown and described.

MAX KLEIN.
